UNITED STATES PATENT OFFICE.

HENRY G. TILLINGHAST, OF BALTIMORE, MARYLAND.

FLOAT-VALVE.

SPECIFICATION forming part of Letters Patent No. 633,351, dated September 19, 1899.

Application filed May 10, 1899. Serial No. 716,251. (No model.)

To all whom it may concern:

Be it known that I, HENRY G. TILLINGHAST, a citizen of the United States, residing at Baltimore, in the State of Maryland, have invented 5 certain new and useful Improvements in Float-Valves, of which the following is a specification.

This invention relates to an improved supply-valve for water tanks or reservoirs which 10 are operated by a float and rod in the tank, whereby the valve is opened by the outflow and closed by the inflow of water automatically.

The object of the invention is to provide an 15 improved valve whereby the movement of the valve is not at all affected by the preliminary outflow or inflow and whereby the operation of opening and closing the valve will be quick and prevent the usual noise accompanying 20 the operation of ordinary valves of this class.

The invention is illustrated in the accompanying drawings, in which—

Figure 1 is a vertical longitudinal section through a tank wherein my improved valve is 25 employed and shows the usual float and rod connecting the valve. Fig. 2 is a vertical section, on a larger scale, through a portion of the valve and shows the construction and relative arrangement of the parts when the valve 30 is closed. Fig. 3 is a detail of a portion of the vertical plunger-stem carrying the rocker-cam. Fig. 4 illustrates the valve, the parts being in the position they assume when the water is running. In this figure the valve-lever 35 is suitable for a faucet.

In the drawings, A designates a valve-casing having an extension a, which is designed to connect with a supply-pipe. In the valve-case, above the extension, is a port b, through 40 which a vertically-movable valve-stem c passes. This stem c carries at its lower end and below the port an elastic or ball valve d, which is secured in place on the stem by a nut e. A spiral spring e' has position in the 45 extension a beneath the valve d and serves to press the valve to its seat. One end of said spring bears on the valve, and the other end rests on a screw-plug f, retained in said extension. Above the port b is a chamber g, 50 from which is an opening g', that permits the water to discharge into the tank when the valve d is unseated. The casing A is also pro-

vided with two vertically-extending arms h, which are inclined a little to one side.

The casing A is provided above the chamber with a vertical bored-out guideway k, down into which the lower end of a plunger m extends. This lower end is tapped and threaded and exteriorly carries a washer l, which fits snugly in said guideway k and 60 makes a water-tight joint and prevents leaking upward through said guideway. The upper threaded end of the valve-stem c takes into the tapped end of the plunger m, and a nut l' compresses the washer. At its upper 65 end the plunger m has two parallel arms n, forming a fork, and a rocker-cam i is free to turn loosely in said fork. The fork and rocker-cam have position between the two vertically-extending arms h on the case. Said 70 plunger m, rocker-cam i, stem c, and valve d have all a vertical movement and are normally moved upward and closed by the pressure of the spring. It will also be seen that by my present construction the valve closes 75 with the pressure of water and is held to its seat by such pressure and opens against the pressure.

A float-lever r is attached by a pivot pin or bolt s between the two arms h on the case. 80 This lever carries at its extremity the ball-float j. This lever has on its under side a notch p, which engages the rocker-cam i. This notch is elongated and is adapted to receive at one end a point of the rocker-cam 85 when the float-lever is raised, as in Fig. 2, and to receive at the opposite end a point of said rocker-cam when the valve is lowered, as in Fig. 4. The lever also has a convex-curved face t on its under side. The rocker-cam i in the present instance has four points i' and a concave face i'' between every two points. This rocker-cam is centrally pivoted and may revolve, though it is not necessary that it shall revolve in its operation. Usually 90 it will simply tilt back when the float-lever comes down and tilt forward when the float-lever goes up. When the valve-lever is down, as in Fig. 4, that point of the rocker-cam i which is in the notch is nearly in line between the pivot-bolt s and the pivot of the rocker-cam, and the convex-curved face t on the lever rests on a concave face i'', and the valve is then held open. 100

Referring to Fig. 4, it will be seen that by a slight modification of the float-lever the valve may be used in the form of a faucet. In this device the long rod and ball-float are dispensed with and a knob *u* is fixed on the lever. A nozzle *q* is also provided which communicates with the chamber *g* of the valve-casing.

The operation of the valve is simple and effective. Suppose the tank to be empty. The float-lever *r* will have the position shown in Fig. 4, with the notch *p* engaging the rocker-cam *i* and pressing same and plunger down. This lowered position causes the rod *m* and valve-stem *c* to be pushed down against the spring *e'* and the valve *d* to be unseated from contact with the port *b* and permits the water to pass up. In this position the rocker-cam *i*, having a concave face, receives the convex-curved face on the lever, and one of the points of the rocker-cam takes in the notch *p*, and the lever is thus retained in the lowered position, as already explained. As the tank or reservoir fills the float will gradually rise and cause the lever to gradually rise. During the preliminary part of this operation (the gradual rising of the lever) no vertical movement is imparted to the plunger-rod and valve-stem *c*. Nearly all of the preliminary movement of the lever is taken up by the tilting of the rocker-cam *i*, which is caused by the notch *p* changing its position and carrying the rocker with it until the point of the rocker is carried past the line of its pivot-point, whereupon by the action of the spring *e'* it will be thrown over to the position shown in Fig. 2, and the rod and valve-stem will immediately be forced upward by the action of the spring and the valve instantly closed.

Having thus described my invention, what I claim as new, and desire to secure by Letters Patent, is—

1. The combination of a casing having a chamber provided at one side with an inlet-port and at the opposite side with a guideway; two stationary upward-extending arms, *h*, attached to the casing; a plunger fitting

movably in said guideway, the upper end of said plunger being slotted and forming fork-arms, *n*, which latter have position between the said two stationary arms of the casing; a rocker-cam, *i*, having a concave face, *i'*, and a projecting point, *i''*, at each end of said face and pivoted between the said two fork-arms of the plunger; a valve-rod extending through the chamber and inlet-port and one end of which is secured to the said plunger; a valve attached to the other end of the rod outside of the chamber, and a float-lever pivoted between the said two upward-extending arms of the casing and provided with a notch, *p*, which engages first one and then the other projecting point of said rocker-cam, substantially as described.

2. The combination of a casing having a chamber provided with an outlet-port, a central guideway and two stationary arms projecting above the chamber; a removable bottom provided with a central opening which forms a valve-seat and having a screw-threaded tubular extension, *a*; a plunger passing through said guideway and having at one end a slot which forms two fork-arms, *n*; a rocker-cam, *i*, pivoted between said two fork-arms and independently movable therein; a valve-rod extending through the chamber one end of which is secured to the plunger and the other end passing through the central opening in the bottom of the chamber and into the tubular extension, *a*; a valve attached to the rod and having position in the said tubular extension; a spiral spring in the tubular extension and pressing the valve on its seat, and a float-lever pivoted between the said two upward-extending arms of the casing and contacting with the pivoted rocker-cam, substantially as described.

In testimony whereof I affix my signature in the presence of two witnesses.

HENRY G. TILLINGHAST.
